UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

CIGAR HOLDER AND ASH RECEPTACLE.

Application filed July 2, 1919. Serial No. 308,091.

To all whom it may concern:

Be it known that I, FRANZ A. FULLER, a citizen of the United States, residing in the city of Newark, in the county of Essex and State of New Jersey, have invented 5 certain new and useful Improvements in Cigar Holders and Ash Receptacles, of which the following is a full, clear, and exact description, such as will enable others 10 skilled in the art to which it pertains to make, construct, and use the same, reference being had to the accompanying drawings, and to characters of reference thereon, forming a part of this specification. 15 My invention has reference to improvements in combined cigar holder and ash receptacle, for the placing therein of cigar ashes, burnt matches, and the like, and provided with means for supporting cigars, 20 cigarettes, etc.

This invention relates more particularly to a novel construction of a combined cigar holder and ash receptacle, comprising an upper and a lower shell, the lower shell at 25 its upper edge being provided with holding means, and the upper shell at its lower edge being provided with locking means, said locking means having locking engagement with said holding means, the upper shell 30 being further provided with an aperture in which is pivotally mounted upon a horizontal rod extending across said aperture, a dish-shaped tray composed of separate half portions, said half portions being provided 35 with apertured lugs by means of which they are pivotally connected to said rod, the half portions being provided with contacting portions designed to engage with the wall of the aperture to limit the upward movement thereof, each of said half portions having 40 a horizontal extension and acting in the double capacity of a cigar rest and as a handle for moving said half portions.

The principal object of this invention 45 therefore, is to produce a cigar holder and ash receptacle, for the purposes above enumerated, which shall be neat in appearance, and shall be of a simple, strong and durable construction, thus providing a device consisting of but two parts, said parts being 50 of such shape as to lend themselves readily to manufacture by the use of suitable punches and dies from ordinary sheet metal, and can be readily and conveniently taken 55 apart for the purpose of removing the

ashes, burnt matches, etc., and then again assembled.

My present invention therefore consists in the novel construction of a combined cigar holder and ash receptacle embodying 60 the principles hereinabove mentioned, and of a character to be more fully described in the following specification.

This invention consists furthermore in the several novel arrangements and combinations of the various parts, as well as in the details of construction of the same, all of which will be hereinafter more fully set forth and then finally embodied in the 70 clauses of the claims which are appended to this specification.

The invention is fully illustrated in the accompanying drawings, in which—

Figure 1 represents, a side elevation, partly in section, of the preferred form of 75 my improved device.

Figure 2 represents, a plan view of the same.

Figure 3 represents, a bottom view of the 80 upper shell; and

Figure 4 represents, a plan view of the lower shell.

Similar characters of reference are employed in all of the above described views 85 to indicate corresponding parts.

Referring now to the said drawings, the reference character 1 indicates the complete device, which consists essentially of an upper and lower shell, namely, the lower 90 ash receptacle 2 and the upper shell 3, secured to said ash receptacle in a manner hereinafter described.

A dish-shaped tray composed of separate 95 half portions is pivotally mounted upon a horizontally arranged rod, which is conveniently secured in any desired or convenient manner to the upper portion of the upper shell, preferably on the inside thereof, through which ashes, matches, etc., may pass into the lower shell or ash receptacle 2.

The lower shell or ash receptacle 2 is formed as shown in the drawings, of a single piece of suitable sheet metal, the circumferential edge being provided with a plurality 105 of integral holding ears 4, extending outwardly therefrom, said ears 4 being preferably four in number to correspond with the recesses 5 formed in the inturned flange 6 which is located on the lower circumferential edge of the upper shell, said flange 110

forming a guide for centering said holder 3 on the ash receptacle 2.

The integral ears 4 on the ash receptacle are designed to enter the recesses 5 formed 5 in the flange 6 so that when the sections are turned in opposite directions the ears will have frictional engagement with said flange and will be interlocked therein and guided thereby, thus securely locking the two sections 10 together and preventing accidental separation thereof.

Extending across the aperture in the upper shell is a horizontal rod 7, adapted for removing the ashes from the end of a cigar, 15 the ends of which are preferably secured in apertured brackets 8—8, which are secured to the inside of the upper shell in any desired or convenient manner and located in close proximity of said aperture.

20 Pivottally mounted upon the horizontal rod 7 is a dish-shaped tray composed of separate half portions 9—9, said half portions being provided with apertured lugs 13—13 by means of which they are pivotally connected to said rod 7, said half portions 9—9 being further provided with downwardly extending portions 11—11 designed to engage with the wall 12 of the aperture to limit the upward movement of 25 said half portions, and each of said half portions being further provided with horizontal extensions 10, acting in the double capacity of a cigar rest and as a handle for moving said half portions when it is desired 30 to permit the ashes, matches, etc., to pass 35 into the lower shell or ash receptacle 2.

The operation of my device is readily seen from the drawings. By lifting either one or 40 both of the cigar rests or horizontal extensions 10 of the two separable half portions of the tray they are caused to tilt in opposite directions and deposit their contents in the ash receptacle 2, and upon return of said 45 half portions to their normal position they act as a closed cover for the upper shell.

By rotating the upper and lower shells 3 and 2 they may be separated without turning the device upside down when it is desired to either separate the two sections for the purpose of cleaning them or putting 50 them together after they have been separated.

Experience has demonstrated that the organization above described is a highly efficient one, and while I have shown the preferred embodiment of my present invention, 55 I do not wish to be limited to the exact details of construction shown and described, as obvious modifications thereof, not involving the exercise of invention, may be made 60 by any skilled mechanic, and such departures from what is herein set forth, I consider within the scope and terms of my claim.

I claim.—

65 In a combined cigar holder and ash receptacle provided with means for detachably connecting both pieces, apertured brackets secured on the inside of one of said pieces, a horizontal rod having its ends secured in said brackets and adapted for removing the ashes from the end of a cigar, a dish-shaped tray composed of separate half-portions provided with apertured lugs for pivotally suspending said half-portions 70 from said rod, downwardly extending parts on said half-portions for limiting the upward movement of the same, and upper horizontal extensions on each of said half-portions constituting cigar rests and handles 75 for manipulating said half-portions to permit ashes and matches to pass into the lower, shell-shaped piece of the holder and receptacle.

This specification signed and witnessed 80 this 30th day of June, 1919.

FRANZ A. FULLER.
